(57) **CLAIM**

The ornamental design for a coffee machine for commercial purposes, as shown and described.

DESCRIPTION

Figure 1.1 is a perspective view of a coffee machine for commercial purposes showing my new design;

Figure 1.2 is a front view thereof;

Figure 1.3 is a left side view thereof;

Figure 1.4 is a right side view thereof;

Figure 1.5 is a top view thereof;

Figure 1.6 is a bottom view thereof; and

Figure 1.7 is a rear view thereof.
